PATENTED MAY 5, 1908.

P. J. MATTER.

ELECTRIC SIGNALING APPARATUS FOR RAILROADS.

APPLICATION FILED DEC. 19, 1907.

UNITED STATES PATENT OFFICE.

PAUL JULIUS MATTER, OF COSWIG, GERMANY.

ELECTRIC SIGNALING APPARATUS FOR RAILROADS.

No. 886,620.

Specification of Letters Patent.

Patented May 6, 1908.

Application filed December 19, 1897. Serial No. 407,126.

To all whom it may concern:

Be it known that I, PAUL JULIUS MATTER, citizen of the Republic of Switzerland, residing at Coswig, Saxony, Germany, have invented certain new and useful Improvements in Electric Signaling Apparatus for Railroads, of which the following is a specification.

My invention relates to improvements in electric signaling apparatus for railroads, whereby in the event of a train approaching another on the same track, either from in front or from behind, a visible signal, and if desired an audible alarm, is given automatically to both engine drivers of the impending danger.

My invention also relates to means whereby the drivers of the two locomotives may communicate with each other with the aid of the automatic signaling plant.

The signal plant may also be employed to announce at railroad stations the arrival of trains and the direction in which they are running.

My invention is illustrated in the accompanying drawing, in which—

Figure 1 is a diagrammatic elevation showing the system of working, and Fig. 2 a diagrammatic plan. Fig. 3 is a cross section through the locomotive. Fig. 4 is a perspective view of a signal box. Figs. 5 and 6 are sectional views of a switching device for use on the locomotive. Fig. 7 is an elevation of an audible alarm device.

The track A is furnished with a parallel line a, which in the drawing is shown as an overhead line carried by posts b, though it might equally well lie, for instance, close beside the track A. The line a does not consist of a single continuous-conductor, but is constituted by a succession of sections c, c¹, c² etc., which are insulated from each other.

For each section c, c¹ etc. a signal box d (Fig. 4) is provided, containing four incandescent lamps, two of which g, h are located in the upper part and the other two i, k in the lower part of the box. The boxes may conveniently be mounted on the posts b which carry the line a. The lamps are connected in the following manner: One top and one bottom lamp (h, i respectively) of each box are connected by wires j, j¹ respectively with the track A. Such top lamp (h) is also connected with a top lamp (g) of the next box (say d²); which latter lamp (g) is connected with the one end of a section of the

line a, the other end of said section being connected with a bottom lamp (k) of the next box again (d³); which lamp (k) is connected with a bottom rail-connected lamp (i) of the succeeding box (d⁴).

The locomotive B has a dynamo l mounted on it, one pole of which is connected through the wheels with a rail of the track A and the other pole by a conductor l¹ with a rod whose trolley or sliding contact m runs on the line a. In Fig. 3 a locomotive is shown having two rods and contacts m m¹, one for use in each of the two directions of running.

Suppose the locomotive B (Fig. 1) to be running in the direction of the arrow X and to occupy the position shown. It is obvious that two parallel circuits will be closed, viz., l—A—j—h—g—c²—m—l¹—l and l—A—j¹—i—k—c²—m—l¹—l. Thus behind the locomotive B two lamps will burn, viz. a top one g in box d² and a top one h in box d³, while in front of the locomotive B also two lamps will light up, viz. a bottom one h in box d² and a bottom one i in box d³. Hence the driver of a train traveling in the direction of the arrow X, whatever section of the line a he may be passing at the time, always sees the bottom part of each of the boxes of the two front sections lighted up, and likewise the illuminated top part of each of the boxes of the two rear sections. Naturally if the train is traveling in a direction opposite to that of the arrow X the engine driver will, on the other hand, observe before him the top (not the bottom) part of each of the boxes of the two front sections illuminated, and behind him the bottom (not the top) part of each of the boxes of the two rear sections.

If, therefore, owing to negligence, or wrong operation of a rail switch or the like, two trains approach on the same track, the driver of each will see before him both the top and bottom of the boxes of the two front sections illuminated and he consequently will know that there is danger ahead. Thus suppose a train to be traveling in the direction of the arrow X (Fig. 1) and to have arrived at the section c: the lamp k in box d¹, and lamp i in box d² will light up. If then a train approaches in the opposite direction and reaches the section c³, the lamp g in box d² and h in box d³ will burn. Thus both drivers will see both lamps i, h burning in box d² and will thus be warned long in advance—that is while still separated by two sections of the line a—that there is danger impending.

Even should one of the drivers—say that of the train traveling in the direction of the arrow X—overlook the danger signal and arrive at the section c' , the danger signal will still continue to be given to him. For the train which has stopped at the section c^3 will continue to light up the lamp g in box d^3 and lamp h in box d^2 , while the train now at section c' will cut in the lamp k in box d^2 and i in box d^3 . Thus in both the boxes d^2, d^3 the lamps will burn at top and bottom and the driver of the approaching train is, as it were, doubly warned of the imminent danger.

The signal boxes may conveniently be constructed as shown in Fig. 4. The box d has four walls e and a glass front and back e^1 . Dark yellow or ruby or like glass should be employed for these windows so that while the glass normally appears dark it will be brightly illuminated when a lamp burns behind it. The interior of the box is divided into a central compartment f^1 and two corner compartments f^2, f^3 by means of diagonal partitions f, f of metal or other opaque material. The two said upper lamps g, h are located in the compartment f^2 and the two lower ones i, k in the compartment f^3 . The central compartment f^1 is provided for the purpose of preventing possible confusion due to the sun or moon shining upon the box. For in such event the box would present the appearance of being illuminated by a lamp burning in both compartments f^2, f^3 , so that the driver would assume that a danger signal was being given and would be unnecessarily caused to stop or take other steps to prevent collision. If, however, he sees that not only the top and bottom corners of the box, but also the central portion shows up bright, he will at once know that the simultaneous illumination of the two corners is not to be interpreted in this case as a danger signal, but is due to some extraneous cause, viz. to the rays of the sun or moon.

In the event of a train approaching another on the same track from the rear, the danger signal will be given with equal certainty. For supposing B (Fig. 1) to be the locomotive of the front train, the driver on it will see behind him the lamp g in box d^2 and lamp h in box d^1 ; and when the second train has arrived at the section c he will also see the lamp i in box d^3 and lamp k in box d^1 , that is to say, the boxes d^1, d^2 will be illuminated both at top and bottom and will thus signal danger to both drivers.

Instead of distinguishing the lamps by location, the distinction may be made by other means, for example colors; thus for instance the part of the window in front of the lamps g, h may be of one color, and the part in front of the lamps i, k of another color.

The drivers of the two trains caused to stop by the danger signal can readily communicate with each other if on both engines

a switch n (Fig. 3) is inserted in the wire l . For by making and breaking circuit they can cut the lamps in and out so as to transmit messages for instance on the Morse system.

Should there be sharp curves, or embankments or the like obstructing a clear view of the track, auxiliary lamp boxes may be located on the line a between two main boxes. Such auxiliary boxes only require to be furnished with one lamp at each corner. Like auxiliary boxes might be fixed at bridges, level crossings and like dangerous places, fitted with glass windows of distinctive color so as to inform the engine driver precisely of the nature of the spot. It may occur at such places that the line a cannot be run at the normal height, but must be elevated. The short interruption of the circuit thus caused is, however, of no importance; the boxes can be so located that the contact is promptly made again. The signal boxes d may also be employed at railroad stations to indicate the approach of a train and its direction of travel. For this purpose it is merely necessary to fix a box at a convenient part of the station and inscribe on its window at the upper and lower corners respectively, for instance: "Train traveling in the direction of —".

In the case of a double track railroad, each track must naturally be provided with a line a and signal boxes.

If a train has to stop for any reason at some part of a double track railway and it is desired to block not only the track on which it is standing but also the neighboring track, it is merely necessary for the driver to connect a reserve wire with the line a of the second track, whereby the latter will be blocked just as effectively as if the engine were on it.

It may happen that the locomotive gets derailed and the connection at m , a is thus broken. To provide for such emergencies an accumulator car may be included in the train, so that a substitute may be at hand for the dynamo. The pole with sliding contact m may in such case be replaced by a spare wire carried in the car.

When the dynamo is driven by the locomotive, so that it ceases to run when the train stops, an accumulator o (Fig. 3) may be provided and the wire l run to it, instead of to the dynamo, when the train is standing still. The accumulator could be conveniently switched in by employing a change-over switch which is thrown over by the reversing lever of the engine. Or the devices shown in Figs. 3, 5 & 6 might be used. On the engine axle p^1 there is keyed a disk p on which there slides the contact spring or brush l^1 of the conductor l . q is a radial arm on which slides a contact block r controlled by a spring s . On the dynamo housing there is provided a surface presenting two concentric contact rings t, u , connected respectively with the dynamo and the accumulator. The

block *r* normally makes contact with the ring *u* so that the accumulator circuit is completed; but when the engine is running, the block *r* flies out owing to the centrifugal force, overcoming the action of its spring *s*, and will thus make contact at *t*, whereby the accumulator is cut out and the dynamo thrown in. By selecting the spring *s* of suitable strength the dynamo can be thus cut in only when the speed of the train is such that the dynamo is driven at a sufficiently high speed to supply the requisite current.

To provide for foggy weather an audible signal may be combined with the visible one. Such a device is shown in Fig. 7. It consists of an electromagnet *z* inserted in a shunt circuit *y* of the conductor which connects the lamp *g* of one signal box with the lamp *h* of the next box; and of an electric siren or the like *v* inserted in a shunt *w* of the conductor connecting the lamp *i* of the first said box with the lamp *k* of the second said box. The armature of the electromagnet *z* is pivoted at *x*² and comprises two parts *x*, *x'* separated from each other by an insulating strip *x'*. The shunt *y* is normally broken. If, however, a current flows through the shunt *y*, the excited electromagnet *z* attracts its armature which turns at *x*² and completes the siren circuit at *x*, *v*. The siren, however, does not sound, since there is no current passing in the shunt *w*. It is only when a current flows through both shunts *w* and *y* simultaneously that the siren will sound and this is obviously only the case if two trains approach on the same track. The entire audible alarm apparatus may be accommodated within the signal box *d*.

Having thus described my invention, I claim as new:

1. An automatic railway signaling apparatus, comprising a track, a sequence of conductor-sections, insulated from each other, and located beside the track, both ends of each section being connected with it, a lamp connected in circuit at each end of each section, the lamp at the end of one section being located adjacent to the lamp at the commencement of the neighboring section, and a traveling source of electricity always in circuit with the track and with one of the sections, substantially as described.

2. An automatic railway signaling apparatus, comprising a track, a plurality of signal stations each comprising two distinctive groups of signals, and sectional conductors all insulated from each other, and each of which has its ends connected with the track, and each of which connects four lamps in series, namely a lamp of a like signal group at each of two adjacent stations with a lamp of the other signal group at each of the two following stations, that portion of the conductor which lies between the two intermediate

stations constituting a traveling-contact wire, all the said sectional conductors being so located relatively to each other that the contact-portion of each lying between the two intermediate stations of each four consecutive ones together constitute a substantially continuous path for a traveling contact, a traveling contact, and a traveling source of electricity connected in circuit with the track and with said traveling contact, substantially as described.

3. An automatic railway signaling apparatus, comprising a track, a sequence of conductor sections, insulated from each other, and located beside the track, both ends of each section being connected with it, a lamp connected in circuit at each end of each section, the lamp at the end of one section being located adjacent to the lamp at the commencement of the neighboring section, and a traveling source of electricity and a switch always connected in circuit with the track and with a conductor section, substantially as described.

4. In combination, a rotary axis, a disk mounted fast thereon and having a radial arm and a spring actuated contact-block sliding thereon, two concentric contactings against the inner of which the said block normally lies, while on rotation of the disk at a certain speed the block flies out and contacts with the outer ring, a battery connected with the inner ring and a dynamo connected with the outer one, and a contact sliding on the disk and connected in circuit with the battery and also with the dynamo, substantially as described.

5. An automatic railway signaling apparatus, comprising a track, a sequence of conductor-sections, insulated from each other, and located beside the track, both ends of each section being connected with it, a lamp connected in circuit at each end of each section, the lamp at the end of one section being located adjacent to the lamp at the commencement of the neighboring section, a traveling source of electricity always in circuit with the track and with one of the sections, an electromagnet shunted in one section at each lamp station, and a pivotal armature, and a contact maker operated thereby and a siren both shunted in open circuit in the other section at the same station, whereby when the electromagnet is excited it attracts the armature and causes the contact maker to close the shunt, substantially as described.

In testimony whereof I affix my signature in presence of two witnesses.

PAUL JULIUS MATTER.
